UNITED STATES PATENT OFFICE.

WILLIAM F. SMITH, OF POUGHKEEPSIE, NEW YORK, ASSIGNOR OF ONE-HALF TO
HERMAN A. SCHATZ, OF POUGHKEEPSIE, NEW YORK.

EXHAUST MANIFOLD AND MUFFLER.

Application filed January 12, 1925. Serial No. 1,904.

This invention relates to an improved exhaust manifold and muffler for internal combustion engines, and more particularly to a device of this character for use with the air cooled internal combustion engine of the type disclosed in my copending application Serial No. 715,338, filed May 23, 1924, and divisions thereof.

The object of the present invention is mainly simplicity of construction and therefore cheapness of assembly, as well as efficient operation.

In accordance with the present invention the pipe through which the exhaust gas passes is cooled by a draft of air. This will prevent the exhaust manifold from preheating the air which is intended to cool the engine cylinders. Preferably, the draft of air is produced in a passageway associated with the muffler and the air and exhaust gases escape together through an opening in the muffler casing. In this manner the exhaust gases are used in creating the draft by suction. This draft of air aids in cooling the muffler which is mounted on top of the hood enclosing the gas engine.

While the invention is disclosed as applied to a particular type of engine, it will be obvious to those skilled in the art that it is applicable also to other types.

In the drawings, Fig. 1 is a perspective view of the muffler; Fig. 2 is a vertical cross-section of the exhaust manifold and the muffler; Fig. 3 is a bottom view of the manifold and muffler; and Figs. 4 and 5 are sectional views along lines 4-4 and 5-5 of Fig. 2.

Referring now to the drawings, the bottom 4 of a cast iron casing 1 is seated on a hood 5 enclosing the engine proper (not shown) and is fastened thereto by means of bolts 2 passing through bosses 3 provided in the bottom 4. The exhaust gases of the engine are expelled through a pipe 6 and a pipe 7 fastened to the former by bolts such as 8 in the direction of the arrows. Near the upper end of the exhaust manifold pipe 7 an annular sloping seat 9 is formed which fits within a correspondingly sloping annular opening 10 formed in the bottom of casing 1. The pipe 7 is drawn tight into this seat by means of a bolt 11 projecting through the top of the casing 1 and an extension 14 of the pipe 7.

The gases arising through the pipe 7 enter through the annular opening within the cas-

ing 1 and flow therethrough in a left-hand direction (Fig. 3) in the upper half (as viewed in this figure) of the casing 1. The gases are forced to flow in this part of the casing by virtue of the fact that the inside 60 of the casing is longitudinally divided into three compartments by means of an inverted sheet metal trough 15 (Fig. 4) extending between baffle plates 16 and 17. These baffle plates are cast integrally with casing 1 and 65 project from the rim 4 thereof in opposite directions about two-thirds across the casing 1. The side walls 18 and 19 of the trough 15 are substantially in alignment with the free ends of the baffle plates 16 and 17. The 70 lower ends of these side walls 18 and 19 are bent back, as shown at 20 and 21, and the trough is held in place by these bent-back portions being clamped between the hood 5 and the edges of a longitudinal opening 12 75 in the bottom of casing 1.

The baffle plate 17 deflects the exhaust gases through perforations 22 in the forward part of wall 18 into the trough 15. The baffle plate 16, blocking the other end of the trough, deflects the gases through perforations 23 provided in the rear part of the side wall 19, whereupon the gases flow out into the lower section of the casing (Fig. 3) and past the gap between the end of the baffle plate 17 and the side of casing 1 through an aperture 26 in the end of the casing 1. During the circuitous passage through the casing or muffler the gases expand, whereby the noise of their escape will be considerably 90 reduced. The expansion of the gases is aided by the provision of longitudinal ribs or fins 30 cast in the top of casing 1.

As previously stated, the invention is particularly applicable to air cooled engines in which the cylinders are, in the well-known manner, provided with fins or webs against which air is blown or drawn. Air drawn past a hot exhaust pipe 7 would not materially aid in cooling the cylinders. In order to remedy this, the exhaust pipe 7 is cooled in the following manner: A sloping sheet metal trough or passageway 30' is fastened to the bottom of the hood in any suitable manner. The trough 30' has an inlet opening at 31 near the exhaust pipe 7. The end of the trough 30' is below an opening 32 in the hood 5 which registers with apertures 33 and 34 in the bottom of the casing 1. The apertures 33 and 34 form the inlet open-

ings of tubes 35 and 36 forming an integral casting with the front end of casing 1. Owing to the draft created by the exhaust gases escaping through the slot 26, suction will be applied to orifices 37 and 38 in the tubes 35 and 36, causing the flow of air in the direction of the arrows through the trough 30' and thence out to the atmosphere with the exhaust gases. The continuous passage of air through the trough 30' will cooperate in the cooling of the exhaust manifold and will cause the exhaust gases to rise after they leave the slot 26, thus protecting the operator against noxious fumes.

15. What I claim is:

1. In an exhaust manifold for internal combustion engines, a casing having cooling fins on one side thereof and an air duct on the other side thereof, two baffle plates projecting from opposite side walls partly across said casing, two longitudinal walls between said baffle plates and substantially parallel with the side walls of the casing, one of said longitudinal walls being provided with apertures only near one and the other only near the other baffle plate, an exhaust gas intake port between one of said baffle plates and the rear wall of said casing, and an exhaust gas exit port in the front wall of said casing.

2. In an exhaust manifold for internal combustion engines, a casing one end wall of which is slotted and the bottom of which is provided with four openings, two baffle plates dividing said casing into three longitudinal intercommunicating sections, one containing a pair of said openings, and the others the third and fourth of said openings, a trough inserted in said casing through said third opening between said baffle plates, the side walls of said trough dividing said casing into three transverse compartments, one of said side walls having perforations adjacent one and the other having perforations adjacent the other baffle plate, two tubes cast integral with said casing and extending from said pair of openings towards said slotted end, an exhaust pipe seated in said circular opening, and an enclosed passageway leading from a point adjacent said exhaust pipe to said pair of openings.

3. In an exhaust manifold for internal combustion engines, a cast iron casing one end wall of which is slotted and the bottom of which is provided with a pair of openings, two baffle plates cast integrally with the casing and dividing it into three longitudinal intercommunicating sections, one containing said pair of openings, the second said oblong and the third said circular opening, a trough inserted into said casing through said oblong opening between said baffle plates, the side walls of said trough dividing said casing into three transverse compartments, one of said side walls having perforations adjacent one and the other having perforations adjacent the other baffle plate, two tubes cast integral with said casing and extending from said pair of openings towards said slotted end, an exhaust pipe seated in said circular opening, and an enclosed passageway leading from a point adjacent said exhaust pipe to said pair of openings.

4. A muffler for internal combustion engines comprising a casing having therein a plurality of passageways for exhaust gases, said passageways serving to conduct the gases in a circuitous path through the said casing, an intake and a discharge opening for said gases, a tapered air duct having for one wall a wall of said casing, said air duct having its large end near the said intake opening and its small end near the said discharge opening and a port interconnecting the small end of said air duct with the interior of said casing at a point adjacent said exhaust opening.

In testimony whereof, I have signed my name to this specification this 3rd day of January, 1925.

WILLIAM F. SMITH.
